UNITED STATES PATENT OFFICE.

HERMANN F. T. ERBEN, OF SCHENECTADY, NEW YORK, ASSIGNOR TO GENERAL ELECTRIC COMPANY, A CORPORATION OF NEW YORK.

BRUSH-HOLDER.

No. 905,675.

Specification of Letters Patent.

Patented Dec. 1, 1908.

Application filed October 17, 1903. Serial No. 177,431.

To all whom it may concern:

Be it known that I, HERMANN F. T. ERBEN, a citizen of the United States, residing at Schenectady, in the county of Schenectady, State of New York, have invented certain new and useful Improvements in Brush-Holders, of which the following is a specification.

The object of my present invention is to improve the construction and operation of brush-holders of dynamo-electric machines.

One of the particular objects of my invention is to improve brush-holders in such a manner as to better fit them for use with high speed machinery, though all of the features of my invention are not limited to such use.

My invention consists in certain features of construction and arrangement all of which will be pointed out in the claims annexed to and forming part of this specification.

For a better understanding of my invention, reference may be had to the accompanying drawings in which I have illustrated one embodiment of it.

Of the drawings, Figure 1 is an elevation showing the brush-holder and a portion of the commutator with which it coöperates; Fig. 2 is a plan of the brush-holder; Fig. 3 is a perspective view illustrating the construction of the pivot brush-carrying frame; Fig. 4 is a perspective view; and Figs. 5 and 6 are elevations showing a slightly modified form of brush-clamping means.

Referring to the drawings, 1 represents the stationary member of the brush-holder. This member which is preferably made of cast metal is adjustably mounted upon a brush-holder carrying stud or member 2 which is shown as passing through a hole formed for the purpose in the stationary member 1. A set-screw 3 at the rear end of the member 1 bears against the stud 2 to rigidly secure the member 1 to the stud in any desired position. The member 1 is formed at one end with a recess 4 in which the spirally coiled end of a spring 5 is located. The inner end of the spring 5 passes through a slot 6 formed in a bolt 7 which passes transversely through and is journaled in the side walls 4' of the recess 4. The head of the bolt 7 has swiveled to it a lever or handle 8 by means of which the bolt 7 may be rotated to vary and adjust the tension of the spring 5. Suitable teeth 9 are

carried by the member 1 by which the lever 8 may be locked in different angular positions.

A pin 10, preferably formed of steel, passes through a hole formed in the member 1 being located so that it is between the stud 2 and the commutator when the brush is in its operative position. The ends of the pin 10 project and upon the projecting ends the movable member 11 of the brush-holder is pivotally mounted. The member 11 of the brush-holder is preferably formed out of sheet metal such as sheet steel. It consists of a pair of portions 12 which may be parallel and which embrace the member 1. These portions are formed with elongated openings 13 through which the stud 2 passes. A connecting portion 14 unites the side portions 12 to which it is substantially perpendicular. A projecting portion or lip 15 extends substantially perpendicularly from the upper edge of the portion 14. A bolt 16 extends perpendicularly from the portion 14 near its center part preferably being riveted to said portion. Apertures are formed in the sides 12 in which the ends of pin 10 are journaled. Preferably the portions 12, 14 and 15 of the member 11 are all parts of a single piece of sheet steel which may be punched or otherwise worked into the form desired.

The brush 23 is clamped against the front face of the portion 14 of the pivot frame with its upper end abutting against the under surface of the portion 15. As a means for clamping the brush to the pivot frame I prefer to employ a spring washer 17 which surrounds the bolt 16 and bears against the front side of the brush which is apertured to receive the bolt 16. A clamping nut 18 threaded on the end of the bolt 16 is used to force the washer against the brush.

In practice I prefer to place a piece of sheet copper 19 or the like between the brush and the portion 14 of the frame. A flexible conductor or "pigtail" 20 has one end secured by soldering or in any other suitable manner to the plate 19. The other end of the flexible conductor 20 is clamped to the upper side of the member 1 by a clamping screw 21. The free end 5' of the spring 5 which is curved reversely to the curve of the spiral portion bears against the portion 15 of the pivot frame to urge the brush into contact with the commutator 22. This arrangement of the spring is an important fea-

ture as the bow of the spring gives the necessary clearance for the screw 21 and the flexible conductor 20.

I have shown in full lines the position of 5 the pivoted frame when a considerable extent of the brush is unconsumed. The position of the frame indicated by the dotted lines in this figure is the one assumed when the brush is nearly reduced to its minimum 10 operative length. It will be observed that the parts are so arranged that the position of the brush upon the commutator does not change materially as the brush is consumed. It will also be observed that the apertures 13 15 formed in the side walls of the frame 11 are arranged so that the stud 2 does not interfere with the normal movements of the pivoted frame but when the brush is practically worn away the rear portions of the sides 12 20 will engage with the stud 2 and thus prevent the frame from engaging the commutator to the detriment alike of the commutator and frame.

In the construction shown in Figs. 4, 5 25 and 6 the spring washer 17 is formed with a flanged portion 17' which bears against the upper end of the brush. A pair of radial ribs or projections 24 are formed on the outer surface of the washer 17. These 30 ribs engage in radial grooves 25 formed for the purpose in the inner end of the clamping nut 18. The engagement between the ribs 24 and the grooves 25 locks the clamping nut to the spring washer and prevents relative 35 rotation between them, at the same time the flanged portion 17' prevents a rotation of the washer with respect to the brush. I find this construction quite desirable in some cases as owing to the inelastic character of 40 the carbon brush and to the fact that the temperature to which the brush is raised has a tendency to modify the resiliency of the spring washer there is a tendency for the brush to become loose unless special preventive means are adopted.

A brush-holder constructed in accordance with my invention as hereinbefore described is exceedingly compact, simple and efficient and possesses many advantageous qualities 50 among which are the following. The frictional forces retarding the movements of the movable member of the brush-holder are reduced to a minimum by the use of the small pivot pin. The movable member of the 55 brush-holder is very light and it has a small moment of inertia which is important, especially for use in high speed machines.

What I claim as new and desire to secure by Letters Patent of the United States, is:

60 1. In a brush-holder, a fixed member provided with a transverse aperture through which a supporting stud may pass, and a movable member pivoted to said fixed member at a point one side of said aperture and 65 provided with a portion normally out of en-

gagement with the stud but adapted to engage the stud to prevent a movement of the movable member into a position in which it would engage the commutator.

2. In a brush-holder, a fixed member provided with a transverse aperture through which a supporting member may be passed, a movable brush-carrying frame provided with portions which embrace the fixed member, a pivotal connection between the fixed member and the brush-carrying member at a point at one side of the aperture, and apertures formed in the sides of the embracing members, the walls of said apertures normally clearing the supporting member but arranged to engage it to prevent an excessive movement of the frame.

3: In a brush-holder, a fixed member, and a movable brush-carrying member pivoted to said fixed member, the movable member being formed out of sheet metal and being provided with an integrally formed lip or extension against which the upper end of the brush abuts, said movable member having also a portion parallel to the length of the brush and provided with means for securing the brush thereto.

4. In a brush-holder, a movable brush-carrying frame formed out of sheet metal which comprises two parallel portions, a connecting portion against which one side of the brush rests, and an extension or lip against which the upper end of the brush abuts, and means on said connecting portion for clamping the brush thereto.

5. In a brush-holder, a pivoted frame to which the brush is rigidly secured, provided with a projection or lip against which the upper end of the brush abuts, and a spring having an adjustable spiral portion, and a portion which is reversely curved with respect to the spiral portion bearing against said projection.

6. In a brush-holder, a fixed member, a movable member pivoted thereto to which the brush is rigidly secured, and a curved spring and a pivot by which one end of the spring is supported and about which a portion of it is coiled in an inverse direction to said curve, the pivot being carried by the fixed member and the other end of the spring being arranged to force the brush against the commutator.

7. In combination, a stationary brush-holder member provided with an aperture, a supporting stud passing through said aperture to which the said stationary brush-holder member is rigidly secured, and a movable brush-carrying frame to which the brush may be rigidly clamped provided with portions which embrace the stationary member of the brush-holder, the embracing portions being provided with apertures through which the supporting stud may pass and being pivoted to the stationary member at one

side of its stud-receiving aperture, the stud-receiving apertures of the movable member being somewhat larger than the stud whereby a limited pivotal movement of the movable member may take place.

8. In combination, a brush and a holder therefor, comprising a stationary member and a movable member pivoted to said stationary member, said movable member being formed of a single piece of sheet metal bent into the form of a U and having the leg portions thereof engaging with said stationary member, the yoke portion of said movable member being arranged parallel to the length of the brush, and means for clamping the brush against said yoke portion.

9. In a brush-holder, a stationary member having a recess formed in it, a movable member pivotally connected therewith, and a tension spring, one end of said spring being formed into a spiral, said spiral end being placed in the recess in the stationary member and the other end of said spring being arranged to engage the movable member.

10. In a brush-holder, a stationary member having a recess formed in it, a movable member pivotally connected to the stationary member, flexible means electrically connecting the movable and stationary members, and a tension spring having a portion at one end curved spirally and placed in the recess in the stationary member, the other end of said spring engaging the movable member and a portion between said other

end and said coiled end being curved reversely to the curve of the spiral portion to clear the flexible means connecting the two members.

11. In combination, a brush and supporting means therefor comprising a stationary member, a U-shaped brush supporting member formed out of sheet metal the ends of which are pivotally connected to said stationary member, means for securing the brush to said support with one of its sides in engagement with the yoke of said support, said means including a bolt passing transversely through the brush and the yoke, and means for limiting the pivotal movement of said U-shaped member to prevent engagement between it and the commutator.

12. In combination, a brush and supporting means therefor comprising a stationary member, a U-shaped brush-supporting member formed of a single piece of sheet metal and having its legs pivotally connected to the stationary member and its yoke portion arranged parallel to the length of the brush, means on said yoke portion for clamping the brush thereto, and means for limiting the pivotal movement of said U-shaped member to prevent engagement between it and the commutator.

In witness whereof, I have hereunto set my hand this 16th day of October, 1903.

HERMANN F. T. ERBEN.
